MACHINE FOR USE IN APPLYING PRESSURE
TO SHOE BOTTOMSJohn T. Lancaster, Newton, Mass., assignor to
United Shoe Machinery Corporation, Paterson,
N. J., a corporation of New Jersey

Application September 5, 1933, Serial No. 688,182

13 Claims. (Cl. 12—36)

This invention relates to improvements in machines for use in applying pressure to shoe bottoms and is herein illustrated as embodied in a machine for cement attaching soles to shoes.

5 It is an object of my invention to provide a machine having improved means co-operating with a shoe receiving pad or pads for holding shoes thereon while the sole attaching pressure is applied. The illustrated machine is of that 10 type in which a plurality of shoe receiving pads are carried by or are connected to form an endless conveyor, each of the pads, in accordance with a feature of my invention, being provided with a slidably mounted standard carrying a 15 holddown which serves as an abutment to receive the thrust of the sole attaching pressure transmitted thereto by the shoe and last. As illustrated herein, and in accordance with other features of my invention, each standard is provided 20 with latching means which may be actuated to hold it in operative position, and means is provided at an operating station at which the pads are successively presented by which the operator can cause the standards of the successive pads to 25 be moved into and latched in operative position prior to the application of the sole attaching pressure. While the invention is disclosed herein as embodied in a conveyor-type machine, it should be understood that in various of its aspects it is applicable also to machines of other 30 types.

With the above and other objects and features in view the invention will now be described in connection with the accompanying drawings and 35 pointed out in the claims.

In the drawings,

Fig. 1 is a sectional view of a cement sole attaching machine of the endless conveyor type embodying my invention;

40 Fig. 2 is a detail view on a larger scale of one of the shoe receiving pads with its slidable standard and holddown, showing in section a latch by which the standard and holddown may be secured in operative position; and

45 Fig. 3 is a sectional view on the line III—III of Fig. 2.

Each of the shoe receiving pads 10 of the illustrated machine comprises an air-tight bag of rubber or other suitable material provided with 50 an intake valve 12 through which air under pressure may be introduced and with an exhaust valve 14 through which the compressed air can be released after a suitable interval. These may be the well-known Schrader valves, or any other 55 suitable type of valve may be used. The bags 10,

which may be reinforced and/or covered, if desired, in any suitable manner, are housed in metal box-like members 16, hereinafter spoken of for convenience as "boxes." Similarly each bag 10 and its box 16 is hereinafter called for convenience a "pad box."

5 Each pad box is provided at each end with a pair of rolls 18 journaled thereto, as indicated at 20 (Fig. 2), running in channelled-shaped tracks 22 carried by a frame 24, the tracks being provided with upper and lower parallel portions, shown in cross section in Fig. 1, connected at their ends by semi-circular portions. The successive pads are connected, as shown at 26, to a pair of endless chains 28. Thus the pad boxes 15 are connected to or form an endless conveyor which may be moved step by step by any suitable mechanism.

Each pad box is provided with holddown mechanism illustrated generally at 30 at the top of 20 Fig. 1 and controlled by mechanism actuated by a treadle 32 located at what may be termed the operating station. Each of the holddown mechanisms, one of which is provided for each of the pad boxes, comprises a standard 34 25 mounted for rectilinear sliding movement in a bracket 36 secured to the box 16 at one side thereof in such manner that the standard extends vertically and may be slid in that direction when the pad box is at the operating station. 30 One of these holddowns will now be described, assuming it to be in the position which it occupies while the pad box is at the operating station.

Secured to the upper end of the standard 34 35 is a goose-neck 38 to the end of which is secured a horizontal rod or bar 40 extending lengthwise of and above the pad 10. Adjustably clamped to the rod 40 are a last engaging abutment 42 and an abutment 44 arranged to 40 engage the forepart of a shoe S on the pad 10. A spring 46, the lower end of which is housed in a socket 48 (Fig. 2) formed in the bracket 36 and the upper end of which is housed in a socket 50 formed in the lower end of the goose-neck 38, is strong enough to lift the column 34, the goose-neck 38 and the holddown carried thereby. To lower the standard 34 at the appropriate time a plate 52 is secured to the lower end of the standard 34 underlying, when at the 50 operating station, a plate 54 (Fig. 1) which is secured to the upper end of a vertically slidable rod 56 carried by a casting 58 mounted on a part of the frame 24. The lower end of the rod 56 is connected by a pivot, slide block and slot 55

connection 59 to the end of an arm of a bell crank lever 60 fulcrumed at 62 to a portion of the casting 58, the end of the other arm of the bell crank 60 being pivoted at 64 to a link 66 the other end of which is pivoted at 68 to the end of the upwardly extending arm of another bell crank lever 70. The bell crank lever 70 is fulcrumed at 72 to the frame 24 and its other, horizontally extending, arm is connected by a rod 74 to the treadle 32. A spring 76 tends to rock the bell crank lever 70 in a counterclockwise direction, as viewed in Fig. 1, thereby rocking the bell crank lever 60 in a clockwise direction and lifting the rod 56 until a collar 78 secured to its lower end contacts with a portion of the casting 58. Thus it will be seen that by depression of the treadle 32 the operator can pull the rod 56 downwardly and by reason of the engagement of the plate 54 with the plate 52 can depress the standard 34 thereby bringing the abutments 44, 42 into engagement with a shoe and last on the pad 10.

Means, which will be described later, is provided for latching the standard 34 in its depressed position in which it is held while compressed air is introduced into the pad 10 through the valve 12 thereby applying the sole attaching pressure. The compressed air is introduced through a movable nozzle 80 carried on the end 25 of a slidably mounted pipe 82, the nozzle 80 being provided with a valve (not shown) for preventing the escape of the compressed air until the nozzle is brought into engagement with the nipple of one of the valves 12. The pipe 82 30 may be moved by any suitable mechanism. For example, the machine may be provided with a treadle 84 pivoted to a treadle rod 86 the upper end of which is pivoted to a bell crank lever 88 fulcrumed at 90 to the frame 24. The other 35 arm of the lever 88 is pivoted to a link 92 the further end of which slides through a sleeve 93 pivoted at 94 to the lower end of a lever 96 which is fulcrumed at 98 to a bracket 100 carried by the frame 24. Preferably the pivot 94 40 passes through a slot extending lengthwise of the rod 92. The other end of the lever 96 is pivoted to a sleeve 102 secured to the pipe 82. A tension spring 104 anchored at one end to a 45 collar 106 carried by the frame 24 and at the other end to a collar 108 secured to the rod 92 tends to move the rod 92 to the right as illustrated in Fig. 1, thereby raising the treadle 84. A compression spring 110, which surrounds the rod 92, bears at one end against the sleeve 93 50 and at the other end against a collar 112 clamped to the rod. Thus it will be seen that when the treadle 84 is depressed the air tube 82 will be moved to the right as viewed in Fig. 1, the force however being yieldably transmitted by 55 the spring 110 and when the treadle 84 is released the tube 82 will be withdrawn by a force which is exerted by the spring 104. It should be understood that the details of the mechanism for controlling the admission of the compressed air are no essential part of my invention and may be varied as desired.

The standard 34 is provided near its lower end with a series of ratchet teeth 120 (Fig. 2) arranged to cooperate with a detent or pawl 122 carried by the end of a hollow plunger 124 which is mounted for horizontal sliding movement in a passage-way formed in the bracket 36. A finger 126 extends upwardly from the sleeve 124 through 60 a slot in the bracket 36 and is engaged by the

outer end of a compression spring 128 the inner end of which is housed in a hole formed in the bracket 36. Thus the spring 128 tends to urge the sleeve 124 away from the standard 34 thus releasing the detent 122 from the ratchet teeth 120. 5 A plunger 130 housed in a casting 132 secured to the casting 36 is provided with a head 134 received within the hollow of the plunger 124. A compression spring 136, housed within the plunger 124, is of such length that it may be engaged 10 by or disengaged from the head 134 of the plunger 130. Thus it will be seen that pressure upon the plunger 130 will tend to compress the spring 136 and will move the plunger 124 to the left, as viewed in Fig. 2, so that the detent 122 will be 15 brought into cooperative relation with the ratchet 120 thereby permitting downward movement of the standard 34 to operative position with the consequent compression of the spring 136 but preventing upward movement of the standard 34 20 until the detent 122 is released.

Means is provided at the operating station by which the plunger 130 may be caused to operate the detent 122 and this is herein disclosed as operated by the treadle 32 in such a manner as to 25 cause the latch mechanism to be rendered operative before the standard 34 is pulled down. Accordingly, a rod 140 is mounted at the side of the box 16 for sliding movement parallel to the rod 34. The rod 140 is provided with a head 142, a 30 portion of which, when the pad box is at the operating station, lies within the path of movement of the plate 54 which, it will be remembered, is carried by the rod 56 and is operative, when the treadle 32 is depressed, to move the standard 35 34 and the holdown 30 into operative position. A tension spring 144 is anchored at one end to the plate 142 and at the other end to a pin 146 which is carried by the box 16. Thus the spring 144 tends to lift the rod 140 when the pad box is at 40 the operating station, the parts normally assuming the position shown in the upper portion of Fig. 1. A lever 150 is fulcrumed at 152 to each of the boxes 16 and is connected by a pin-and-slot connection 154 with the rod 140. The other 45 end of the lever 150 is provided with a cam member 156 arranged to engage the plunger 130 and, when the rod 140 is depressed by the actuation of the treadle 32, to force the plunger 130 to the left, as viewed in Fig. 2, thereby compressing the 50 spring 136 and forcing the pawl 132 into operative relation with the ratchet 120, the arrangement being such that the plate 54 contacts with the plate 142 and depresses the rod 140 before the plate 54 reaches the plate 52. Therefore, by 55 the time the downward movement of the standard 34 is started the pawl 122 will be in operative position ready to engage the ratchet 120 and hold the standard in any position to which it may be depressed.

In the operation of the device, before each pad box reaches the operating station it will have passed means (not shown) for operating the exhaust valve 14 thereby relieving the air pressure in the pad and so reducing the pressure between the pawl or detent 122 and the tooth of the ratchet 120 which it engages that the spring 128 can move the sleeve 124 to the right, as viewed in Fig. 2, thereby releasing the standard 34 which is thereupon lifted by its spring 46. Thus, when the pad box reaches the operating station, the operator can remove the shoe at once and can immediately replace it with another suitably prepared shoe and sole. He will then depress the treadle 32 thereby moving the pawl 122 to its op- 75

erative position and depressing the standard 34 and the holddown 30 with its abutments 42, 44. If he wishes he may introduce a little air into the pad 10 by momentarily depressing the treadle 84 so as to facilitate the handling of the shoe as the abutments 42, 44 are brought down. After the latter have been brought down to the desired position, in which they are held by the detent 122 and ratchet 120, the operator depresses the treadle 84 thereby moving the nozzle 80 into engagement with the valve 12 and inflating the bag 10 to the desired extent. Then the operator releases both treadles and the pad box is in condition to maintain the pressure while it passes around the circuit and until it reaches the means for operating the release valve 14.

Having thus described my invention, what I claim as new and desire to secure by Letters Patent of the United States is:

20 1. A machine for use in applying pressure to work pieces comprising a plurality of pad boxes each with a work piece receiving pad contained therein, a holddown mounted on a single standard located at one side of each pad box, manually operated means for depressing said standards successively as they are presented thereto to bring the respective holddowns into operative relation to work pieces on the respective pads, and latch mechanisms carried by the pad boxes operable 25 to hold the standards depressed relatively to the pads.

2. A machine for applying pressure to shoe bottoms having, in combination, a shoe receiving pad, a pad box containing the pad and provided 30 with a bracket in which is mounted a vertically sliding standard carrying abutments constructed and arranged to engage a shoe and last in operative position on the pad, treadle actuated mechanism for depressing said standard and abutments 35 relatively to the pad to hold a shoe in operative position on the pad, a latch carried by the pad box and arranged to hold said standard in depressed position, and connections whereby displacement of the treadle of said mechanism also 40 operates said latch.

3. A machine for applying pressure to shoe bottoms having, in combination, a pad provided with a single vertically sliding standard carrying a last engaging abutment constructed and arranged 45 to engage the cone of a last in operative position on the pad and an abutment formed and arranged to engage the forepart of a shoe on said last, treadle actuated mechanism for depressing said standard and abutments relatively to the 50 pad to hold the last and a shoe mounted thereon in operative position on the pad, and a latch for holding said standard in depressed position.

4. A machine for use in applying pressure to shoe bottoms comprising a shoe receiving pad, a standard located at one side of the pad, a shoe engaging device mounted thereon, a latch, and manually operated mechanism operable first to render the latch operative to hold the standard against movement from the pad and then, while 55 the latch is in said operative condition, to depress the standard thereby applying pressure to the shoe on the pad.

5. A machine for use in applying pressure to shoe bottoms comprising a pad constructed and arranged to receive a sole and a shoe positioned thereon, shoe and last engaging abutments mounted on a single standard located at one side of the pad, treadle actuated means for depressing said standard to bring the shoe and last engaging 60 abutments into operative relation to a shoe which

is to be clamped to a sole on the pad, and pawl and ratchet mechanism operable to hold the standard depressed relatively to the pad.

6. A machine for use in applying pressure to shoe bottoms comprising a shoe receiving pad, a single standard located at one side of the pad, a shoe engaging device mounted thereon, pawl and ratchet mechanism, and treadle actuated mechanism operable first to render the pawl and ratchet operative to hold the standard against movement from the pad and then, while the pawl and ratchet are in said operative condition, to depress the standard thereby applying pressure to the shoe on the pad.

7. A machine for use in applying pressure to shoe bottoms comprising a flexibly connected series of inflatable shoe receiving pads forming an endless conveyor, a shoe engaging device mounted on a standard located at one side of each pad, means for depressing the standards to bring the shoe engaging devices into operative relation to shoes on the pads, a latch operable to hold the standard depressed relatively to each pad, and means for introducing fluid under pressure into the pads.

8. A machine for applying pressure to shoe bottoms having, in combination, a conveyor comprising a plurality of shoe engaging pads connected by an endless flexible member, each pad being provided with a rectilinearly movable holddown member constructed and arranged to engage a shoe in operative position on the pad, mechanism for moving said holddown members rectilinearly toward the respective pads to hold shoes in operative position on the pads, and a latch for holding each of said members in depressed position.

9. A machine for applying pressure to shoe bottoms having, in combination, a conveyor comprising a plurality of inflatable shoe engaging pads connected by an endless flexible member, each pad being provided with a slidable holddown member constructed and arranged to engage a shoe in operative position on the pad, mechanism for sliding said holddown members toward the respective pads to hold shoes in operative position on the pads, a latch for holding each of said members in depressed position, and means for introducing fluid under pressure into the respective pads.

10. A machine for applying pressure to shoe bottoms having, in combination, a conveyor comprising a plurality of shoe engaging pads connected by an endless flexible member, each pad being provided with a vertically sliding holddown member constructed and arranged to engage a shoe in operative position on the pad, operator controlled mechanism for depressing said holddown member relatively to the pad to hold a shoe in operative position on the pad, and means for holding said member in depressed position.

11. A machine for applying pressure to shoe bottoms having, in combination, a conveyor provided with a plurality of pads formed and arranged to receive shoes to which pressure is to be applied, each pad being provided with a holddown member vertically movable toward and from operative position relatively to a shoe on the pad, a latch for securing each holddown member in depressed position, and treadle actuated mechanism arranged to depress the holddown of one of the pads and then to cause the latch of that pad to secure the holddown in depressed position.

12. A machine for applying pressure to shoe bottoms having, in combination, an endless con-

veyor provided with a plurality of inflatable pads formed and arranged to receive shoes to which pressure is to be applied, each pad being provided with a holdown member rectilinearly slidable 5 toward and from operative position relatively to a shoe on the pad, means for sliding the successive holdown members toward the respective pads, a latch operated by said sliding means for securing each holdown member in depressed 10 position, and manually controlled means for inflating the pads.

13. A machine for applying pressure to shoe bottoms having, in combination, an endless con-

veyor provided with a plurality of fluid filled pads formed and arranged to receive shoes to which pressure is to be applied, each pad being provided with a holdown member vertically movable 5 toward and from operative position relatively to a shoe on the pad, a latch for securing each holdown member in operative position, and a manually operable controller arranged first to put the latch of a pad at an operating station 10 into operative condition and then to depress said holdown member thereby causing the latch to hold it in depressed position.

JOHN T. LANCASTER.
